CIRCULATION PUMP DRIVE AND FUEL SHUT-OFF CONTROL FOR FORCED CIRCULATION BOILERS

David M. Schoenfeld, Scarsdale, N. Y., assignor to Combustion Engineering, Inc., New York, N. Y., a corporation of Delaware

Application December 22, 1949, Serial No. 134,514

10 Claims. (Cl. 112—448)

This invention relates to steam generators that are equipped with forced circulation pumps having both high capacity and low capacity driving means, and it has special reference to activating such driving means in proper accordance with the steam loading on the generator and to protecting the generator from overheating should the pump-produced water circulation through the boiler tubes fall below the minimum called for by the steam loading on the generator.

Broadly stated the object of my invention is to accomplish the foregoing activation and protection automatically and in a simple yet highly reliable manner.

A more specific object is to provide improved means responsive to a measure of the steam load supplied by the generator for causing the circulation pump to be driven at low speed when said load is less than a given value and at high speed when the load exceeds that value.

Another object is to provide cooperating means that are effective to cut off the fuel supply to the boiler should the pump, when driven either at high speed or at low speed, fail to circulate water through the steam generating tubes at a rate adequate for the steam load being carried by the boiler.

Other objects and advantages of the invention will become apparent from the following description of illustrative embodiments thereof when taken in conjunction with the accompanying drawings wherein:

Fig. 1 is a diagrammatic representation of my new control system applied to a steam generator that is equipped with a forced circulation pump which has a low-speed driver in the form of a low capacity electric motor and a high-speed driver in the form of a higher capacity steam turbine; and

Fig. 2 shows how the control and protective facilities of Fig. 1 may be applied to a forced circulation boiler whose pump is driven by a single electric motor which operates at low speed when energized over one connection and at high speed when energized over another connection.

The illustrative steam generator to be benefitted

The steam boiler represented utilizes the usual separating drum 10 connected in customary manner to receive steam and water mixture from steam evaporation tubes 12 and to discharge water through downcomer pipe 13 to water circulation pump 14 which forces that water into distribution header 15 for flow therefrom into the lower ends of tubes 12. The aforesaid evaporation tubes 12 (only one of which is indicated in Fig. 1) extend as shown from the header 15 through the generator's combustion chamber 17 and thence to the drum 10.

Boiler water is circulated by pump 14 through the steam evaporation tubes 12 at rates equal to several times the weight of steam that is evaporated in the tubes and discharged from drum 10 to steam outlet 18. If desired a check valve (not shown) may be interposed between pump 14 and header 15 for the purpose of assuring that water circulation can proceed only in the direction (as indicated by the arrows) of from pump 14 through tubes 12 to drum 10 and thence back to the pump.

As here shown the evaporation tubes 12 are housed within walls 20 forming the aforesaid furnace chamber 17; at the upper portion of said chamber the tubes may pass back and forth to form the illustrated convection bank; and within the furnace offtake 21 there may be located a superheater 22 leading from drum 10 to outlet 80 header 23 and thence to steam discharge conduit 18. As

2

other arrangements of generator pressure parts are both possible and common, it will be understood that the forced circulation organization here schematically disclosed is illustrative rather than restrictive.

5 Fuel for firing the represented steam generator may be introduced into combustion chamber 17 in any suitable manner as through the medium of one or more burners 25. Only one such burner 25 is here shown, and the form thereof has been simplified to facilitate explanation. It will be assumed that this burner 25 is designed to utilize fuel oil supplied thereto from a suitable source represented at 26; as the description proceeds it will become apparent that other burner designs (as oil recirculating) and other fuels (as gas or coal) also are useable in the boilers to which my invention is applicable.

10 Adjustment in the rate at which the represented burner 25 injects the burning fuel into furnace chamber 17 may be effected in any suitable manner as through the medium of an adjustor valve 27. Setting of valve 27 to hold the generated steam pressure, as indicated at gage G, at a desired constant value may be accomplished either manually or automatically, as through the medium of conventional adjustor means indicated generally at 28.

15 Regardless of whether such adjustment is effected manually or automatically, high steam loadings on the generator will call for correspondingly high rates of fuel supply to burner 25 through valve 27; intermediate steam loadings on the generator will call for an intermediate setting of fuel adjustor valve 27; and low steam loadings will require that valve 27 be opened only the small amount needed to supply fuel burner 25 at a corresponding low rate. In other words a flow of fuel through the fuel supply pipe 26 and burner 25 is controlled in accordance with the steam load on the generator 12 to maintain the desired boiler operating pressure; steam load being defined as the pounds of steam per hour consumed by steam utilizing apparatus and supplied by the generator at a (for all practical purposes) constant pressure which may be either the designed pressure of the boiler of some other predetermined pressure. When the adjustment of valve 27 is effected automatically the conventional adjustor means 28 would of course take the form of an intricate modulator control device which would be effective to maintain the aforementioned constant pressure. This result is brought about by gage G responding to the pressure in header 23 by moving the indicator and other mechanism (not shown) either in the clockwise or counterclockwise direction in response to an increase or a decrease of pressure in said header 23 from its predetermined constant value which increase or decrease is brought about by a change in the load on the generator. If the load increases the pressure in header 23 initially falls while if the load decreases the pressure in said header initially rises. In response to the aforementioned moving of gage G adjustor 28 is effective to adjust valve 27 in such a manner as to regulate the fuel supplied to and accordingly the heat input of the boiler so as to restore the pressure in header 23 to the aforesaid constant value.

60 *High-speed and low-speed driving means for circulation pump*

65 The earlier described water circulation pump 14 for the steam generator is shown as receiving driving rotation through a shaft 31 and a gear wheel 32 carried thereby. Meshing with one side of this gear wheel is a first pinion 33 driven by a first prime mover which takes the form of a low capacity electric motor 34; and meshing with the other side of the same pump driver gear 32 is a second pinion 35 driven by a second prime mover which takes the form of a higher capacity steam turbine 36.

70 With this arrangement it is possible to drive circulation pump 14 either by electric motor 34 or by steam turbine 36. Overrunning clutches 37 and 38 may if desired be used in the motor and turbine output shafts so that when the motor 34 is driving the pump it will not be required also to rotate the turbine and so that when the turbine 36 is driving the pump 14 it will not be required also to rotate the motor.

75 As earlier indicated, turbine 36 is of high capacity (as compared to motor 34) and is adapted to drive the cir-

culation pump 14 at the high speed which must accompany high steam loadings on the generator. Motor 34 on the other hand is of lower capacity and is adapted to drive circulation pump 14 at the low speed adequate when the steam generator is operating under low steam loadings. In either event the driven pump 14 functions to deliver water to header 15 at a pressure sufficiently above boiler pressure (in drum 10) to overcome the resistance of the evaporation tube circuits 12 (including orifices therein—not here shown) when pumping the required weight of water corresponding to the steaming rate of the boiler. The weight of boiler water so circulated through the tubes 12 typically will be several times that of the steam being evaporated in those tubes; this ratio varying with the installation.

To facilitate explanation, let it be assumed that the steam turbine 36 has a capacity of 100 horsepower and serves to drive circulation pump 14 at a speed of about 1500 R. P. M.; that electric motor 34 has a capacity of 15 horsepower and serves to drive boiler pump 14 at a speed of approximately 500 R. P. M.; that the latter low speed (500 R. P. M.) of pump operation is adequate for starting up the steam generator and for sustaining steam loadings thereon up to approximately 20%; and that the high turbine speed (1500 R. P. M.) of pump operation is called for only to sustain steam generator loadings in the range above 20% rated capacity.

Control of motor and turbine operation and load-responsive selection therebetween

In the illustrative arrangement shown, steam for driving turbine 36 is supplied thereto from conduit 18 of the steam generator through piping 40 which includes normally closed valve 41; current for driving motor 34 is supplied thereto from power circuit A—B—C through normally opened switch contacts 42; the normally closed turbine valve 41 is provided with a solenoid 44 which when energized effects an opening of the valve and thereby admits driving steam to the turbine 36; and the normally opened motor switch is provided with a solenoid 45 which when energized serves to close switch contacts 42 and supply driving current to motor 34. Deenergization of solenoid 44 is accompanied by reclosure of turbine valve 41 and stoppage of turbine 36; and deenergization of solenoid 45 is accompanied by a reopening of motor switch 42 and stoppage of motor 34.

In accordance with my invention I control the operation of motor 34 and of turbine 36 in response to a measure of the steam load supplied by the generator; this control being accomplished in a novel manner which causes the circulation pump 14 to be driven at low speed by motor 34 when said load is less than a given value (earlier assumed to be 20% of rated generator capacity) and at high speed by the turbine 36 when the steam load exceeds that given value.

For accomplishing such novel control automatically any suitable measure of the steam loading on the generator may be utilized; a steam flow meter SF and a fuel flow meter FF here being shown to provide such required measure.

As here represented, steam flow meter SF is actuated by the pressure drop across an orifice 47 in the steam output line 18; response to the pressure drop across some other part of the supplied steam system, such as superheater 22, is of course also possible for providing the measurement desired. In either event meter SF positions pointer 48 in accordance with the rate at which the generator is supplying steam through output line 18; pointer 48 occupying the extreme left position shown under conditions of zero output, the extreme right position when the generator output is maximum, and intermediate positions for intermediate steam loadings. The represented instrument SF further includes a stationary contact 49 which is disengaged from pointer 48 when the generator steam load is within the range below 20% full rated, and which is engaged by that pointer for all steam loads on the generator of 20% rating or above.

In the illustrative form here shown, the fuel flow meter FF is actuated by the pressure drop across an orifice 51 in the line 26 through which fuel is supplied to burner 25. This meter also is provided with a pointer 52 and a stationary contact 53. When the burner 25 is receiving fuel at low rates corresponding to less than 20% steam loading on the generator pointer 52 is disengaged from contact 53; however when burner 25 receives fuel at rates

corresponding to steam loadings of 20% rated and higher on the generator then pointer 52 engages contact 53.

Since the pressure in header 23 is maintained constant, as hereinbefore explained, it is apparent that the pressure drop across and accordingly the flow through orifice 47 is responsive to and gives an indication of the previously defined steam load on the generator. It is further apparent that since the fuel supply to the generator, i. e., the flow of fuel through the fuel supply conduit, is regulated in accordance with said steam load, as previously explained, a device indicating the flow of fuel through said fuel supply conduit likewise gives an indication of the steam load on the generator. Thus since both of the meters SF and FF are effectively responsive to the steam load on the generator and accordingly give an indication of said steam load either one of these instruments may be utilized to determine when the drive for circulating pump 14 shall be transferred from low speed motor 34 to high speed turbine 36 and vice versa.

Any suitable means for causing either steam flow meter SF or fuel flow meter FF to control the functioning of motor 34 and turbine 36 in the manner aforesaid may of course be employed. Possibilities include hydraulic control devices, air operated control facilities, or electrical circuits and devices. In the embodiment of my invention here disclosed electrical facilities are utilized; but as the description proceeds it will become apparent that such utilization is illustrative rather than restrictive and that hydraulic or air operated means may be substituted without departing from the spirit and scope of my invention.

Forming a part of the "electrical" system represented is a source of control potential designated by vertical conductors 55 and 56 respectively shown at the left and at the right of Fig. 1. Between these "plus" and "minus" conductors there is maintained a suitable control potential such as 110 volts direct current.

Also utilized in the represented control system, for motor 34 and turbine 36 is a load relay LR. This relay is provided with a contact 58 which occupies the released (or lower) position shown as long as the relay winding (shown immediately above the "LR" designation) is de-energized but which moves upwardly to the picked up position whenever the winding of relay LR is connected across supply conductors 55—56.

Control of such connection is accomplished by the steam flow meter SF when a selector switch 59 is in the upward position shown and by the fuel flow meter FF when switch 59 is moved to the downward position. In the description of control system operation now to follow it will first be assumed that switch 59 is up thereby placing the load relay LR under the control of steam flow meter SF.

From the diagram of Fig. 1 it will be seen that as long as a starting switch 60 has the open position shown neither turbine 36 nor motor 34 can be brought into operation. Under this condition solenoids 44 and 45 are both deenergized, turbine valve 41 is closed and motor switch 42 is open.

With the steam generator cold let it now be assumed it is desired to start up same. Starting switch 60 is first closed. This completes for motor switch solenoid 45 an energizing circuit that extends from supply conductor 55 through the solenoid winding 45, conductor 61, back contact 58 of load relay LR, the switch blade 60 and conductor 62 to supply conductor 56.

Thus energized solenoid 45 closes switch contacts 42 thereby connecting motor 34 with energizing circuit A—B—C and placing the motor in operation. Since the generator is producing no steam pointer 48 of flow meter SF keeps load relay LR deenergized, solenoid 44 allows turbine valve 41 to remain closed, and turbine 36 is thus kept inactive. But motor 34, energized as aforesaid, now drives circulation pump 14 at the slow speed of about 500 R. P. M. This causes the pump to circulate water through the steam generating tubes 12 at a rate adequate for steam loadings on the generator of up to about 20% full rated capacity.

The circulation thus having been started, fuel valve 27 can be partially opened and burner 25 lighted to provide in combustion chamber 17 heat which generates in tubes 12 steam that passes into drum 10 and thence through superheater 22 to outlet conduit 18. Low capacity motor 34 will now continue to operate either until starting switch 60 is opened or until the rate of

fuel supply to burner 25 has been raised to a point where the steam loading on the generator rises to above the aforesaid 20% rated value.

When the latter happens, pointer 48 of flow meter SF will engage contact 49 and complete for load relay LR a pick up circuit extending from supply conductor 55 through conductor 63, the winding of relay LR, switch 59, engaged elements 48-49 of meter SF, and conductor 64 to supply conductor 56. Thus energized, relay LR moves contact 58 upwardly to its front point thereby disconnecting motor switch solenoid 45 from supply conductor 56 and connecting turbine valve solenoid 44 therewith.

By reason of said disconnection solenoid 45 allows switch contacts 42 to reopen and shut down the motor 34; said reopening preferably occurring after a short time delay provided in any suitable manner as by the represented condenser 66 bridged across winding 45 and serving to continue current flow therethrough for a short period following the pickup of load relay LR. In practice this delay period may be chosen to span the interval required by turbine 36 to come up to speed following the now initiated opening of steam supply valve 41.

Said steam valve opening is accomplished by solenoid 44 upon the aforesaid pickup of load relay LR; that solenoid then being energized over a circuit extending from supply conductor 55 through the winding 44, front contact 58 of picked up relay LR, closed starting switch 60, and conductor 62 to supply conductor 56. The thus energized solenoid 44 opens normally closed valve 41 and allows steam from the generator outlet header 23 to flow through piping 40 into the pump driving turbine 36. Thus activated the turbine now drives boiler circulating pump 14 at a high speed earlier assumed to be 1500 R. P. M.

When so driven by the high capacity turbine 36 the pump circulates water through steam generating tubes 12 at a rate adequate for loads up to full steam generating capacity of the boiler furnace. As long as this loading remains above 20% rated, flow meter SF keeps pointer 48 in engagement with contact 49, thereby holding load relay LR picked up and causing solenoid 44 to maintain turbine valve 41 open.

Assume next that the steam load on the generator drops to some lower value (as below 20% rated) at which the high speed driving of pump 14 no longer is necessary. When the decrease has reached 20% of rated load, flow meter SF moves pointer 48 to the left away from contact 49. This breaks the pickup circuit of load relay LR and releases contact 58.

Such release disconnects turbine valve solenoid 44 from control conductor 56 thereby allowing turbine valve 41 to reclose; at the same time the now released contact 58 reconnects motor switch solenoid 45 with said conductor 56. Accordingly as the high capacity turbine 36 is taken out of operation the low capacity motor 34 is started up, and circulation pump 14 is again driven at the slow speed earlier assumed to be 500 R. P. M.

Should it be desired to stop the circulation pump 14 completely this may be accomplished merely by opening starting switch 60. Such opening deenergizes solenoid 45 to cause an opening of switch contacts 42 and resultant shut down of the motor pump 34; it likewise isolates turbine control solenoid 44 from energizing conductor 56 thereby making admission of steam to the turbine 36 impossible.

Load-responsive selection from fuel flow meter FF

The foregoing operating sequence for low capacity motor 34 and high capacity turbine 36 is substantially duplicated when the control thereof is shifted from steam flow meter SF to fuel flow meter FF. As earlier indicated such shift is accomplished by moving transfer switch 59 to the downward position wherein the winding of load relay LR is connected with device FF through conductor 68. With this new set up the loading on the steam generator is measured by fuel meter FF the pointer and contact elements 52-53 of which now accomplish the same function as did pointer and contact elements 48-49 of steam flow meter SF.

As long as the burner 25 is supplied with fuel from line 26 at a rate corresponding to steam generator loadings below a given value (earlier assumed to be 20% rated) meter FF keeps pointer 52 disengaged from contact 53. Hence, with starting switch 60 closed load relay LR stays released, motor switch solenoid 45 is

energized over back contact 58, and contacts 42 connect supply circuit A-B-C with motor 34. This causes the low capacity motor 34 to drive boiler pump 14 at the slow speed (assumed to be 500 R. P. M.); high capacity turbine 36 being kept inactive under this condition.

When however the rate of fuel supplied to burner 25 rises to a value corresponding to steam generator loadings above 20% rated, fuel flow meter FF moves pointer 52 into engagement with contact 53. This picks up load relay LR over a circuit extending from supply conductor 55 through conductor 63 and winding of relay LR, transfer switch 59 in its downward position, conductor 68 contact and pointer 53-52 of device FF, and conductors 69 and 62 to supply conductor 56. Load relay LR now again picks up (as before) breaking at back contact 58 the energizing circuit for motor switch solenoid 58 and completing at front contact 58 the earlier traced energizing circuit for turbine valve solenoid 44.

In consequence the high capacity turbine 36 now replaces the low capacity motor 34 in driving circulation pump 14. By reason of its resultant operation at high speed (assumed to be 1500 R. P. M.) that pump now circulates water through steam generating tubes 12 at a rate adequate for the highest steam loadings of which the generator is capable.

Upon drop in the generator steam output the rate of fuel supply to burner 25 drops accordingly and when the load has decreased to about 20% fuel meter FF moves pointer 52 to the left away from contact 53. This breaks the pick up circuit for load relay LR and by releasing contact 58 substitutes low capacity motor 34 for high capacity turbine 36 in driving the circulation pump 14.

As earlier indicated shutdown of the entire system may be effected merely by opening starting switch 60. Moreover, to reassign control of load relay LR back to steam flow meter SF (from fuel flow meter FF) it is only necessary to shift transfer switch 59 back into the upward position.

The just described automatic control of low capacity (motor 34) and high capacity (turbine 36) driving prime movers for circulation pump 14 assures important economies in the energy consumption required to drive that pump. Steam generators of the forced circulation type here illustrated are sometimes operated for prolonged periods at relatively low steaming rates. Under such operating conditions the expenditure of 100 horsepower (assumed for turbine 36) to drive circulation pump 14 represents a considerable wastage of energy over expenditure of only 15 horsepower (assumed for motor 34) which is entirely adequate to drive the pump as long as the steam load stays within the lower range. The automatic control and transfer facilities just described are therefore instrumental in effecting important savings in boiler operating cost.

Overheat protection of boiler by automatic fuel shutoff

Steam generating boilers of the forced circulation type here disclosed require that a minimum rate of water circulation through evaporating tubes 12 be maintained during operation otherwise those tubes may become seriously damaged due to overheating. The complete control system of my invention also provides protection against this possibility.

In the illustrative arrangement here disclosed, such protection is exercised through a shutoff valve 71 disposed in the fuel supply line 26 leading to burner 25. This valve is normally open and thus ordinarily allows free flow of the fuel to burner 25 in any quantity that may be determined by the setting of fuel adjustor valve 27.

In order that shutoff valve 71 may be closed at proper times it is, in the arrangement here shown, provided with a solenoid 72 which can at said proper times be energized from supply conductors 55-56 over a circuit that includes a second contact 74 of load relay LR and contact members in an instrument DP which measures the differential pressures between the inlet and the outlet of boiler circulation pump 14.

When said pump 14 is at rest the differential pressure thereacross is zero and the pointer 75 of instrument DP then occupies the extreme left position shown. As the pump speed builds up it creates between pump inlet 13 and pump outlet 15 a differential pressure which is roughly proportional to the speed at which the pump is rotated

and which serves to force the water from drum 10 through the steam evaporating tubes 12 in the manner earlier explained.

To facilitate explanation it will be assumed that a driving of pump 14 by low capacity motor 34 at 500 R. P. M. produces a differential pressure of about 5 lbs. per square inch and that a driving of the pump by high capacity turbine 36 at 1500 R. P. M. produces an elevated differential pressure of the order of about 35 lbs. per square inch.

Let it further be assumed that when the steam generator is operating in the low capacity range (earlier assumed to be under 20% of full rated) the steam generating tubes 12 will not be in danger of overheating as long as the pump 14 driven by motor 34 at about 500 R. P. M. continues to hold it's differential pressure above 3 lbs. per square inch; and that when the generator is operating at load levels of above 20% rated and pump 14 is being driven by turbine 36 at about 1500 R. P. M. the aforesaid generating tubes 12 will not be subjected to danger from overheating as long as the pump produces a differential pressure of above 15 lbs. per square inch.

On the basis of the foregoing assumptions it is desired that fuel shutoff valve 71 be closed: (a) under low speed operation of pump 14 when and only when the produced differential pressure falls from the stated normal of about 5 lbs. per square inch to a reduced value of 3 lbs. per square inch; and (b) under high speed operation of pump 14 when the produced differential pressure falls from a normal of about 35 lbs. per square inch to a reduced value of about 15 lbs. per square inch.

In order that differential pressure meter DP may translate an indication of such reduction into an energization of fuel shutoff solenoid 72, that instrument is provided with contacts 76 and 77 respectively engaged by pointer 75 through the respective pressure ranges of less than 3 lbs. per square inch and of less than 15 lbs. per square inch. These two instrument contacts 76 and 77 are respectively connected with the back and front points of load relay contact 74 to achieve a functioning now to be described.

Assume first that the steam generator is operating at a loading of less than 20% full rated and circulation pump 14 is being driven at low speed (500 R. P. M.) by motor 34. Under this condition load relay LR is released causing back contact 74 thereof to join the winding of solenoid 72 with low range contact 76 in instrument DP. As long as pump 14 creates a differential pressure higher than 3 lbs. per square inch pointer 75 is kept to the right of contact 76, solenoid 72 is deenergized and the fuel shutoff valve 71 is allowed to occupy its normally open position.

Should now the pump differential pressure fall below 3 lbs. per square inch, instrument DP will move pointer 75 to the left into engagement with contact 76. This will energize shutoff valve 72 over a circuit extending from supply conductor 55 through conductor 79, engaged elements 75-76 of differential pressure meter DP, conductor 80, back contact 74 of released relay LR and the solenoid winding 72 to the supply conductor 56.

Thus energized solenoid 72 closes shutoff valve 71 and discontinues supply of fuel to the burner 25. Such discontinuance lowers the temperature in combustion chamber 17 and thereby protects the steam generating tubes 12 from damage due to overheating.

Assume next that the steam generator is operating in the load range above 20% rated in which circulation pump 14 is being driven at high speed (1500 R. P. M.) by turbine 36. As long as the so driven pump creates a differential pressure of above 15 lbs. per square inch, instrument DP holds pointer 75 to the right of contact 77. As earlier brought out, the load relay LR is picked up during the assumed high capacity loading on the steam generator; hence under the stated condition solenoid 72 is deenergized and fuel shutoff valve 71 is allowed to occupy its normally open position.

Should now the differential pressure produced by pump 14 fall from its normal of about 35 lbs. per square inch to less than 15 lbs per square inch, instrument DP will move pointer 75 to the left into engagement with contact 77. This completes for shutoff valve solenoid 72 an energizing circuit that extends from supply conductor 55 through conductor 79, engaged elements 75-77 of device DP, conductor 81, front contact 74 of picked up relay LR and the winding of solenoid 72 to supply conductor 76.

Thus energized solenoid 72 closes shutoff valve 71 and by stopping further fuel supply to burner 25 lowers the

temperature in combustion chamber 17 and thereby safeguards the steam generating tubes 12 from overheating.

Application of control facilities to single motor pump drive of Fig. 2

In the system of Fig. 1 the low capacity pump driver took the form of an electrical motor 34 having assumed operating speed and rating values of 500 R. P. M. and 15 horsepower, while the high capacity pump driver took the form of a steam turbine 36 having assumed operating speed and rating values of 1500 R. P. M. and 100 horsepower. The novel control and protective facilities of my invention which already have been described also are applicable to situations wherein the low speed and the high speed drives for the pump originate in a single prime mover instead of in two separate prime movers.

One example of such a single prime mover organization is shown in Fig. 2. There the boiler circulation pump 14 is driven by a single electric motor 82 which when energized over a first or "low speed" set of terminals (shown on the lower side thereof) functions as a low capacity machine to drive pump 14 at about 500 R. P. M. and which when energized over a second or "high speed" set of terminals (shown at the upper side thereof) functions as a high capacity machine to drive pump 14 at about 1500 R. P. M. To facilitate explanation it will further be assumed that during said low speed operation the motor 82 develops about 15 horse power and during the high speed operation it's rating is of the order of 100 horsepower.

In the arrangement of Fig. 2 connection of said low speed terminals with power source A-B-C is accomplished by the same switch contacts 42 and activating solenoid 45 as were earlier described for Fig. 1, and connection of motor 82's high speed terminals is effected through normally open switch contacts 41' which at proper times are closed by a solenoid 44' that corresponds to device 44 of Fig. 1.

Comparing the diagram of Fig. 2 with that of Fig. 1 it will be seen that in all other respects there is an exact duplication; the only changes being the just described substitution of two-speed motor 82 for separate prime movers 34 and 36 and the attendant application of the controls respectively utilized for those separate low speed and high speed prime movers to the low speed and to the high speed windings of said motor 82.

Accordingly, the operation of the Fig. 2 system exactly duplicates that already explained in detail for the system of Fig. 1; the only changes being that the low speed facilities of motor 82 come into operation in place of the single motor 34 of Fig. 1 and the high speed facilities of motor 82 come into operation in place of the high speed turbine 36 of Fig. 1.

Because the functioning of the Fig. 2 system is in all other respects exactly the same as the functioning of the Fig. 1 system, no attempt to repeat operation description is here deemed necessary.

Summary

From the foregoing it will be seen that my invention has provided important improvements in the operation and protection of forced circulation steam generators equipped with high-capacity and low-capacity driving means for the forced circulation pump; that one portion of said invention resides in improved means responsive to a measure of the steam load supplied by the generator for causing the circulation pump to be driven at low speed when said load is less than a given value and at high speed when the load exceeds that value; that said facilities effect selection of the driving means and transfer from one to the other automatically and in a simple yet highly reliable manner; and that the invention further provides improved means responsive to the differential pressure created by the pump for protecting the boiler parts from overheating should said pump when driven at either high speed or low speed fail to circulate water through the steam generating tubes at a rate that is adequate for the steam load being carried by the boiler.

Although I have shown an electrical system of control and protection it will become apparent that the same results can be achieved in other ways as through the medium of control facilities actuated either hydraulically or by air pressure.

The particular control and protective arrangement here disclosed is therefore illustrative rather than restrictive.

and my inventive improvements accordingly have broad utility and are capable of wide application.

What I claim is:

1. In a steam boiler, the combination of a combustion chamber, a burner for introducing into said chamber fuel that is to be burned therein, means for supplying said fuel to said burner at a rate adjustable to meet the steam load imposed upon the boiler, steam generating tubes associated with said chamber to receive heat liberated therein by a burning of said supplied fuel, a separating drum receiving from said tubes the steam which said heat generates therein and discharging said received steam to the boiler load, a circulation pump connected to supply to and force through said tubes water taken from said drum, a low-capacity prime mover for driving said pump at a low speed, a high-capacity prime mover for driving said pump at a high speed, means including a first instrument effectively responsive to the aforesaid steam load carried by said boiler for activating said low-speed pump driving prime mover when said load is less than a given value and for activating said high-speed pump driving prime mover when said steam load is greater than said given value, a normally-inactive shut-off device for the aforesaid burner fuel supply means, a second instrument responsive to the differential pressure across said circulation pump for indicating the rate at which that pump circulates water through said steam generating tubes, and means controlled jointly by said second instrument and by said first instrument for activating said fuel shut-off device in the event that said pump when driven by said low-capacity prime mover should fail to circulate water through said generating tubes at a predetermined low rate adequate to sustain steam loadings on the boiler which are below said given value and also in the event that said pump when driven by said high-capacity prime mover should fail to circulate water through the generating tubes at a predetermined higher rate adequate to sustain steam loadings on the boiler which are above said given value.

2. In a boiler of the type described having pump means for establishing a positive circulation through the steam generating tubes of the boiler the improvement comprising first prime mover means operatively associated with said pump means for driving the same at a predetermined high speed, second prime mover means operatively associated with said pump means for driving the same at a predetermined low speed, a control device effectively responsive to the steam load on the boiler and including means associated with each of said prime movers operative to activate the first and deactivate the second prime mover when said steam load exceeds a predetermined value and to activate the second and deactivate the first prime mover when said steam load is less than said predetermined value.

3. An organization as defined by claim 2 wherein the second prime mover comprises an electric motor.

4. An organization as defined by claim 3 wherein the first prime mover comprises a steam turbine.

5. In a steam boiler, the combination of a combustion chamber, a burner for introducing into said chamber fuel that is to be burned therein, means for supplying said fuel to said burner at a rate adjustable to meet the steam load imposed upon the boiler, steam generating tubes associated with said chamber to receive heat liberated therein by a burning of said supplied fuel, a separating drum receiving from said tubes the steam which said heat generates therein and discharging said received steam to said steam load, a circulation pump connected to supply to and force through said tubes water taken from said drum, a low capacity prime mover for driving said pump at a low speed, a high capacity prime mover for driving said pump at a high speed, means effectively controlled by said steam load imposed on said boiler and operable to cause low speed drive of said pump by said low capacity prime mover when said load is less than a given value and high speed drive of the pump by said high capacity prime mover when the steam load exceeds said given value, a normally inactive shut-off device for the aforesaid burner fuel supply means, and means responsive to the rate at which said pump circulates water through said steam generating tubes for activating said fuel shut-off device in the event that said pump when driven by the said low capacity prime mover and when driven by said high capacity prime mover as aforesaid fails to circulate said water at a rate which is ade-

quate for the particular steam load being carried by the boiler.

6. In a steam boiler comprising a combustion chamber in which fuel is burned, steam generating tubes associated with said chamber to receive heat from said burning fuel, a separating drum receiving from said tubes the steam which said heat generates therein and discharging said received steam to steam utilizing apparatus, and a circulation pump connected to supply to and force through said tubes water taken from said drum, the combination of a low capacity prime mover for driving said pump at a low speed, a high capacity prime mover for driving said pump at a high speed, an instrument actuated in response to the rate at which the aforesaid steam generated in said tubes is supplied to said steam utilizing apparatus and means governed by said instrument for activating said low speed pump driving prime mover and deactivating said high speed pump driving prime mover when the aforesaid rate is less than a given value and for activating said high speed pump driving prime mover and deactivating said low speed pump driving prime mover when said rate is greater than said given value.

7. In a steam boiler, the combination of a combustion chamber, a burner for introducing into said chamber fuel that is to be burned therein, means for supplying said fuel to said burner at a rate adjustable to meet the steam load imposed upon the boiler, steam generating tubes associated with said chamber to receive heat liberated therein by a burning of said supplied fuel, a separating drum receiving from said tubes the steam which said heat generates therein and discharging said received steam to steam utilizing apparatus, a circulation pump connected to supply to and force through said tubes water taken from said drum, a low capacity prime mover for driving said pump at a low speed, an operation control device for said low capacity prime mover, a high-capacity prime mover for driving said pump at high speed, an operation control device for said high-capacity prime mover, an instrument responsive to the rate at which said steam generated in said tubes is supplied to said steam utilizing apparatus and means governed by said instrument for activating said low capacity prime mover control device and deactivating said high capacity prime mover control device when the aforesaid steam rate is less than a given value and for activating said high-capacity prime mover control device and deactivating said low capacity prime mover control device when said steam generating rate exceeds said given value.

8. In a steam boiler comprising a combustion chamber in which fuel is burned, steam generating tubes associated with said chamber to receive heat from said burning fuel, a separating drum receiving from said tubes the steam which said heat generates therein and discharging said received steam in accordance with the steam load on the boiler, and a circulation pump connected to supply to and force through said tubes water taken from said drum, the combination of a low capacity prime mover for driving said pump at a low speed, a high capacity prime mover for driving said pump at a high speed, a steam flow meter responsive to the rate at which the steam, generated in said tubes as aforesaid, is taken from said drum to supply the aforesaid load, and means governed by said steam flow meter for activating said low capacity and deactivating said high capacity pump driving prime mover when the aforesaid steam flow rate is less than a given value and for activating said high capacity and deactivating said low capacity pump driving prime mover when said steam flow rate is greater than said given value.

9. In a steam boiler comprising a combustion chamber that is provided with a burner, means for supplying fuel to said burner and for adjusting the flow rate of said fuel to meet the steam load imposed upon the boiler, steam generating tubes associated with said chamber to receive heat liberated therein by a burning of said supplied fuel, a separating drum receiving from said tubes the steam which said heat generates therein and discharging said received steam to said boiler load, and a circulation pump connected to supply to and force through said tubes water taken from said drum, the combination of a low capacity prime mover for driving said pump at a low speed, a high capacity prime mover for driving said pump at a high speed, a fuel flow meter responsive to the rate at which the aforesaid fuel is supplied to said

11

burner for the purpose of generating steam in said tubes, and means governed by said fuel flow meter for activating said low speed and deactivating said high speed pump driving prime mover when the aforesaid fuel supply rate is less than a given value and for activating said high speed and deactivating said low speed pump driving prime mover when said fuel supply rate is greater than said given value.

10. In a steam boiler comprising a combustion chamber, a burner for introducing into said chamber fuel that is to be burned therein, means for supplying said fuel to said burner at a rate adjustable to meet the steam load imposed upon the boiler, a normally inactive shut-off device for said fuel supply, steam generating tubes associated with said chamber to receive heat liberated therein by a burning of said supplied fuel, a separating drum receiving from said tubes the steam which said heat generates therein and discharging the received steam to said load, and a circulation pump connected to supply to and force through said tubes water taken from said drum, the combination of a low capacity prime mover for driving said pump at a low speed when the steam load supplied by said boiler is less than a given value, a high capacity prime mover for driving said pump at a high speed when said boiler steam load is greater than 15.

12

5. said value, an instrument responsive to the differential pressure across said circulation pump for indicating the rate at which that pump circulates water through said steam generating tubes, and means jointly responsive to said instrument and the said steam load on the boiler for activating said fuel shut off device in the event that said pump when driven by said low speed prime mover fails to maintain said water circulation above a predetermined low rate adequate for steam loadings on the boiler which are less than the aforesaid given value, and also in the event that said pump when driven by said high speed prime mover fails to maintain said water circulation above a predetermined higher rate adequate for boiler loadings which are greater than said given value.
